UNITED STATES PATENT OFFICE.

MAX PAUL KRAUTSCH, OF APPLETON, WISCONSIN.

SEWING-MACHINE ATTACHMENT.

1,158,937.

Specification of Letters Patent.

Patented Nov. 2, 1915.

Application filed February 4, 1914. Serial No. 816,531.

To all whom it may concern:

Be it known that I, MAX PAUL KRAUTSCH, a citizen of the United States, residing at Appleton, in the county of Outagamie and State of Wisconsin, have invented new and useful Improvements in Sewing-Machine Attachments, of which the following is a specification.

My invention relates to sewing machines, and particularly to that type in which a rotary hook is revolved about a container adapted to hold a spool of thread.

My invention provides a sewing machine of the type mentioned, which is simple in construction, efficient in operation, easily manipulated, and overcomes the disadvantages and objectionable features of the bobbin type of machine, inasmuch as has already been stated, the machine does not require a particular type of bobbin, the thread container being adapted to receive the ordinary spool such as thread is wound on for market sale.

In the drawings annexed hereto and forming a part of this specification:—Figure 1 is a front elevational view of part of the sewing machine located beneath the work plate and constructed according to my invention. Fig. 2 is a side elevational view of the sewing machine parts illustrated in Fig. 1. Fig. 3 is a bottom plan view of the sewing machine shown in Fig. 1. Fig. 4 is a vertical sectional view through the spool case support and showing in detail the revolving hook. Fig. 5 is a top plan view of the thread container. Fig. 6 is a front elevational view of the rotating carrier.

Throughout the separate views the same part is designated by the same reference numeral.

Referring to the drawings:—The operating shaft 1, which is designed to be driven in the usual manner, is mounted in the bearing block 2 and carries the cam 21, the function of which will be hereinafter set forth. The bearing block 2 is carried by the base plate 11 and the shaft 1 lies longitudinally underneath the said base plate. Also underneath the base plate, beneath the throat plate 3 and in alinement with the shaft 1 and bearing block 2, is mounted the bearing member 4 counterbored at 5 to form

a bearing race 6 in which the revolving hook member 7 rotates, it being retained therein by the ring member 8 secured to the bearing member 4 by means of the screws 9. The shaft 1 carries a crank member 10 which is also guided in the bearing race and engages the rotating carrier 7 imparting to the latter a rotary movement when the shaft 1 is rotated.

On the lower side of the bearing member 4 is mounted the pedestal 12 upon which is adjustably mounted the bracket 13 extending at right angles thereto. At the outer end of the bracket 13 is pivoted the angular arm 14 having one end pivotally connected to the arm 15 which telescopes within the member 16 pivotally mounted on a reciprocating rod 17. The other end of said angular member is bent around as shown to form a hook 18, the entire hook being bent upwardly at an angle to the horizontal plane of the angular arm 14, the latter being pivoted at 19.

The reciprocating rod 17 is mounted in the bearing block 2 in such a manner as to allow for its reciprocating movement which is caused by the engagement of the roller 20 mounted in its end with the cam surface of the cam 21 which revolves with the shaft 1. The reciprocating rod 17 extends forward and carries at its forward end a pin 22 which in turn engages the eye 23 in the member 24 journaled in the pedestal 12. The member 24 has pivotally mounted thereon an arm 25 normally lying in a plane at right angles to the horizontal plane of the member 14. This arm 25 has at its upper end a hook 26 and its lower end 27 extends through the eyelet of the hook 18. It will be seen that from this construction when the reciprocating rod 17 is actuated the arm 25 will first move outward to the position shown in dotted lines, longitudinally across the side of the spool container by reason of the engagement of the pin 22 with the eye 23 in the member 24, however, just before the reciprocating rod 17 reaches the end of its movement, the member 16 which, up to this time has been telescoping with the rod 15, will engage the abutment 28 carried by the latter and move the hook 18 radially thereby imparting to the arm 25 a movement sub-

stantially at right angles to the movement given it by the reciprocating rod 17. Mounted on the pin 29 by which the arm 25 is pivoted to member 24 is a spring 30 having one end secured to the arm 25 as shown and the other end to the member 24 thereby causing the arm 25 to return to its normal position as the reciprocating rod 17 is moved backward due to the action of the spring 17' having one end secured to the other end of the reciprocating rod 17.

Journaled in the pedestal 12 and extending longitudinally with respect to the thread container, is the shaft 31 bent up at right angles to itself to form a finger 32 lying in front of the thread container 33. The shaft 1 carries a second cam member 34 which engages the projecting tongue 35 mounted on the shaft 31 and causes the finger 32 to move back and forth across the end face of the spool container as the shaft 1 rotates. The spring member 31' is mounted on the member 31 and serves to move it backward after the action of the cam has moved it forward. The revolving carrier 7 carries a spindle 35 upon which is preferably mounted the spool container or thread container 33, the latter being held from the rotary movement by means of the engagement of the projection 36 with the locking arm 37, which serves to retain the spool or thread container in place upon the spindle 35. The spool container 33 is slotted at 38 and has mounted thereon the tension member 39, the slot and tension member serving to guide the thread as it is drawn out of the spool container.

In the operation of the machine, as the shaft 1 is rotated the rotating carrier 7 catches the loop of thread pushed down through the thread plate 3 by the needle 40, one side of the loop engaging the hook 42 of the rotating carrier, the other side of the loop being caught by the hook 26 of the arm 25. As the shaft 1 further revolves the arm 25 moves longitudinally across the spool container 33 and the hook 42 carries its side of the needle loop farther around the spool container. When the arm 25 reaches the end of its swing across the spool container 33 it moves downward and hooks the thread onto the finger 32 actuated by the cam 34. This operation serves to bring the loop of thread over the spool container. Upon further revolution of the shaft 1, one side of the loop from the needle is drawn over the end of the spool container and looped around the thread from the latter, the take-up arm then acts to take up the surplus thread in the loop and draws the needle thread and thread from the spool container together to form a lock stitch.

It is to be understood that I do not limit myself to the specific construction and ar-

rangement of parts described and claimed herein but may resort to such modifications as fall within the scope of my invention.

Having thus described my invention, what I claim is:—

1. In a sewing machine, the combination with operating mechanism, of a stationary thread container, a rotating carrier having a spindle adapted to carry said stationary thread container, an arm carrying a hook adapted to move longitudinally of said thread container to the end thereof and thence partially across the container, spring means for returning said arm to its normal position, a finger adapted to move across the front of said thread container, a bearing race for said rotating carrier, and means for operating said rotating carrier, arm and finger whereby the needle loop is carried around the thread container and the thread issuing therefrom and also the rotating carrier to form a lock stitch.

2. In a sewing machine, the combination with the needle operating mechanism, of a stationary thread container adapted to accommodate an ordinary spool, a revolving carrier having a spindle adapted to carry said stationary container, an arm carrying a hook adapted to move across the side of said thread container and partially across the front thereof, a finger adapted to move wholly across the front of said thread container, cam and roller means adapted to impart movement to said arm, and a rotary member carrying said cam adapted to impart movement to said revolving carrier, arm and finger whereby the needle loop is carried around the thread container and the thread issuing therefrom to form a lock stitch.

3. In a sewing machine, the combination with the needle operating mechanism, of a stationary thread container, a revolving carrier supporting said stationary thread container, an arm carrying a hook adapted to move across the side of said thread container and partially across the front thereof, a spring and cam actuated shaft carrying a finger adapted to move back and forth across the front of said thread container, cam and spring actuated means for imparting movement to said arm, and a rotary main shaft adapted to actuate said parts whereby the needle loop is carried around the thread container and thread issuing therefrom to form a lock stitch.

4. In a sewing machine, the combination with the needle operating mechanism, of a stationary thread container, a revolving carrier supporting said stationary thread container, an arm carrying a hook adapted to move across the side of said thread container and partially across the front thereof, means for locking said thread container against ro-

tating movement, a spring and cam actuated finger adapted to move back and forth across the front of said thread container, a reciprocating rod adapted to impart movement to said arm, cam and spring actuated means for reciprocating said rod, and a rotary main shaft adapted to actuate said parts whereby the needle loop is carried around

said thread container and thread issuing therefrom to form a lock stitch. 10

In testimony whereof I affix my signature in the presence of two witnesses.

MAX PAUL KRAUTSCH.
